H. A. TOMARIN

Des. 166,644

COMBINED SHIRT AND COLLAR PROTECTOR

Filed Sept. 12, 1951

FIG. 2

FIG. 1

INVENTOR.

BY HARRY A. TOMARIN

Warren Kinney, Jr.
ATTORNEY

UNITED STATES PATENT OFFICE

166,644

COMBINED SHIRT AND COLLAR PROTECTOR

Harry A. Tomarin, Cincinnati, Ohio, assignor to Loroco Industries Incorporated, Reading, Ohio,
a corporation of Ohio

Application September 12, 1951, Serial No. 16,611

Term of patent 14 years

(Cl. D80—7)

To all whom it may concern:

Be it known that I, Harry A. Tomarin, a citizen of the United States, residing at Cincinnati, in the county of Hamilton and State of Ohio, have invented a new, original, and ornamental Design for a Combined Shirt and Collar Protector, of which the following is a specification, reference being had to the accompanying drawing, forming part thereof.

Fig. 1 is a top plan view of my combined shirt and collar protector, showing my new design.

Fig. 2 is a perspective view of the article of Fig. 1 in set up position.

I claim:

The ornamental design for a combined shirt and collar protector, as shown.

HARRY A. TOMARIN.
